DESIGN FOR A DISPLAY MOUNT FOR
BACKED PHOTOGRAPHIC FIGURESJack Charles Schirrmacher, Jersey City, and Peter James Doran, Woodridge, N. J.

Application August 9, 1941, Serial No. 102,777

Term of patent 14 years

To all whom it may concern:

Be it known that we, Jack Charles Schirrmacher, a citizen of the United States, residing at Jersey City, in the county of Hudson, State of New Jersey, and Peter James Doran, residing at Woodridge, Bergen County, State of New Jersey, have invented a new, original, and ornamental Design for a Display Mount for Backed Photographic Figures, of which the following is a specification, reference being had to the accompanying drawing, forming part thereof.

In the drawing:

for backed photographic figures, showing our design.

The essential features of our design reside in the parts shown in full lines, the broken lines being merely illustrative.

We claim:

The ornamental design for a display mount for backed photographic figures, substantially as shown and described.

JACK CHARLES SCHIRRMACHER.
PETER JAMES DORAN.
